(57) **CLAIM**

The ornamental design for a ruggedized two-way radio, as shown and described.

DESCRIPTION

FIG. 1 is a front elevational view of a ruggedized two-way radio showing our new design;

FIG. 2 is a left side elevational view of the ruggedized two-way radio of FIG. 1;

FIG. 3 is a rear elevational view of the ruggedized two-way radio of FIG. 1;

FIG. 4 is a right side elevational view of the ruggedized two-way radio of FIG. 1;

FIG. 5 is a bottom plan view of the ruggedized two-way radio of FIG. 1;

FIG. 6 is a top plan view of the ruggedized two-way radio of FIG. 1;

FIG. 7 is a front elevational view of an alternative embodiment of a ruggedized two-way radio showing our new design;

FIG. 8 is a left side elevational view the ruggedized two-way radio of FIG. 7;

FIG. 9 is a rear elevational view of the ruggedized two-way radio of FIG. 7;

FIG. 10 is a right side elevational view the ruggedized two-way radio of FIG. 7;

FIG. 11 is a bottom plan view of the ruggedized two-way radio of FIG. 7; and,

FIG. 12 is a top plan view the ruggedized two-way radio of FIG. 7.

The broken lines immediately adjacent the shaded areas represent the bounds of the claimed design while all the other broken lines are directed to environment and are for illustrative purposes only; the broken lines form no part of the claimed design.
